UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

AUTOMATIC LOOM.

Application filed March 18, 1918. Serial No. 223,097.

To all whom it may concern:

Be it known that I, JONAS NORTHRUP, a citizen of the United States, residing at Hopedale, in the county of Worcester and State of Massachusetts, have invented certain new and useful Improvements in Automatic Looms; and I do hereby declare the following to be a full, clear, and exact description of the invention, such as will enable others skilled in the art to which it appertains to make and use the same.

The present invention relates to an improvement in automatic weft replenishing looms.

15 The chief object of the invention is to prevent the formation of double picks during the weaving of the cloth. Further objects of the invention will be pointed out as the description proceeds. A double pick may 20 occur from one of two causes: (1) It occurs on a filling feeler controlled, weft replenishing loom if the filling end extending from the selvage to the bobbin in the shuttle—when the latter is boxed for the replenishing operation—is drawn or whipped into the shed after the replenishing operation; (2) it occurs on both filling feeler controlled and filling detector controlled, weft replenishing looms if the filling 25 end extending from the hopper stud to the selvage after the first pick following the replenishing operation is broken and is drawn or whipped into the shed. Various devices have heretofore been proposed for 30 preventing the formation of double picks, and many of these devices have been extensively used and have accomplished their purposes more or less successfully. The chief difficulty with these prior devices, as 35 it appears to the present inventor, has lain in the uncertainty of their operation in securing and acting upon the filling ends. It is accordingly proposed to overcome this difficulty by so constructing an automatic 40 loom that the various devices thereof forming the subject-matter of the present invention will act uniformly and positively in securing the filling ends, and thereby preventing them from being drawn or whipped into 45 the shed to form double picks. To this end and to the accomplishment of the other objects of the invention, the present invention resides in the structure particularly 50

pointed out in the claims, a specific form of this structure being described in the following specification.

The preferred form in which it is contemplated embodying the invention is illustrated in the accompanying drawings, in which Figure 1 is an end elevation of a portion of a weft replenishing loom, showing the application thereto of the various devices of the present invention for preventing the formation of double picks; Fig. 2 is a sectional plan of the parts shown in Fig. 1, taken on various planes for the purpose of showing the construction more clearly; Fig. 3 is a rear elevation of a portion of the thread clamping and parting mechanism; Fig. 4 is a side elevation of the devices shown in Fig. 1, with the parts in different positions and showing their relation to the lay as the latter moves forward on the replenishing beat-up; and Fig. 5 is a front elevation of the replenishing shuttle box.

Certain features of the present invention are particularly adapted for application to feeler controlled, weft replenishing looms, or feeler looms, as they are more commonly known; and other features of the invention are adapted for application to both feeler looms and filling detector controlled, weft replenishing looms. A feeler loom is a type of weft replenishing loom wherein a filling feeler mechanism is employed to determine the state of exhaustion of the filling in the active shuttle, and when the filling has been exhausted to a predetermined or critical extent, to cause the insertion in the shuttle of a fresh supply of filling by the replenishing mechanism. A filling detector controlled replenishing loom is one in which a filling detector mechanism determines the absence or presence of filling in the shed, and when filling is absent either from breakage or complete exhaustion, causes the insertion of a fresh supply in the shuttle. In feeler looms an intact strand of filling extends from the selvage to the bobbin in the shuttle when the latter is boxed for the replenishing operation. In filling detector controlled looms there is no filling end extending from the selvage to the bobbin about to be ejected from the shuttle. Consequently, it is necessary to provide only feeler looms with devices for preventing the strand of filling

extending from the selvage to the outgoing bobbin from being subsequently drawn into the shed. But in both feeler looms and filling detector controlled, replenishing looms a filling end extends from the stud of the hopper to the selvage after the first pick following replenishment, and so it is necessary in both types of looms for the production of the highest grades of fabric to prevent this filling end from being drawn into the shed.

The automatic weft replenishing loom of the present invention may be of any usual or preferred form wherein the filling is replenished by the insertion in the active shuttle of a filled bobbin, which expels the old bobbin on which the filling may be exhausted either to a predetermined extent, or from which the filling may be completely exhausted. The weft replenishing mechanism, of which the hopper for containing the supply of filled bobbins is indicated in dot and dash outline at 10, is adapted to be thrown into operation by an oscillation to the left, viewing Fig. 1, of the hopper arm 11 secured to and extending upwardly from a hollow change shaft 12. This hollow change shaft 12, when the devices of the present invention are applied to a feeler loom, that is to say, a loom in which the weft replenishing operation takes place on predetermined or critical exhaustion of the filling in the active shuttle, is connected with the filling feeler mechanism; and, on the other hand, when the replenishing mechanism is thrown into operation on the absence of filling, the change shaft is connected with the filling detector mechanism. Both the filling feeler mechanism and the filling detector mechanism may be of any usual or preferred form, and inasmuch as their construction and mode of operation are familiar to those skilled in the weaving art, it is not necessary to an understanding of the present invention to illustrate or describe them. The hollow change shaft 12 and its associated parts are known as the loom controlling devices. When on the indication of either critical exhaustion or absence of the filling the change shaft 12 is oscillated in a direction to swing the hopper arm 11 outwardly, that is, to the left, viewing Fig. 1, the transerrer latch 14 is positioned in the path of the bunter 15, so that, on the following beat-up of the lay the replenishing operation takes place. This beat-up of the lay is known as the replenishing beat-up and usually occurs on the beat-up following the detection of the absence, or the critical exhaustion, of the filling. The transerrer latch 14 is pivoted on the lower end of an arm 16 loosely mounted on a stud 13 fixed in the hopper plate 9, on which the hopper 10 is supported. A pin 20 extending laterally from the inner side of the transerrer latch is engaged by a slot 21 formed

in the lower end of an arm 22 depending downwardly from the hub of an arm 17, which is loosely mounted on the stud 13. The upper end of the arm 17 is yieldingly connected by a spring 18 with an angle piece 19 vertically adjustable on the upper end of the hopper arm 11. The construction and operation of these parts are well known to those skilled in the weaving art.

The prevention of the formation of double picks by the devices of the present invention is in part accomplished by a novel form of replenishing shuttle box. The replenishing shuttle box is the shuttle box located at the end of the lay on the replenishing side of the loom. This shuttle box is indicated generally by the reference character 25. It comprises a bottom plate 26, which is the shuttle race of the lay 27, a back wall or binder 28, a top plate 29, and a two-part front wall indicated generally at 30. The top plate 29 at its inner end extends forwardly over the inner end of the shuttle box, and the front shuttle box wall 30 is provided with a bracket piece or arm 31 which rests on the inner end 24 of the top plate and is adjustably secured thereto by means of a bolt 32. An adjustment screw 33 is provided for the purpose of laterally adjusting the outer end of the upper part 36 of the front box wall. The front box wall 30 of the replenishing shuttle box is composed of an upper part 36 depending from the bracket 31, and a lower part 37 which is bolted to the shuttle race by means of capscrews 38. A narrow longitudinal slot 39 separates the upper and lower parts of the front box wall 30 throughout their entire length. When the shuttle 40 comes to rest in the replenishing shuttle box with its outer end against the picker 41, fastened to the upper end of the picker stick 42 which operates in well-known manner, the eye 43 of the shuttle is at a substantial distance from the outer ends of the front box wall. This is for the purpose of permitting certain of the devices of the present invention to operate on the filling extending from the selvage to the shuttle eye at a point between the outer end of the front box wall and the shuttle eye.

After the weft replenishing operation takes place and before the lay beats backward, the relative positions of the parts are substantially as shown in Figs. 2 and 5. The filled bobbin 45 is in the shuttle and from it there extends a strand of filling 46 under the end plate 44 of the hopper to the hopper stud 47, to which the free ends of the filled bobbins in the hopper are all attached. This strand of filling is known as the incoming filling end. As the lay beats backward after the replenishing operation, the shuttle is picked to the opposite side of the lay, and the incoming filling end 46 being held at its outer end by the hopper

stud 47, draws down onto the threading block 48 in the shuttle. It sometimes happens, however, by reason of the outer extremity of the incoming filling end being held at a point above the top of the threading block 48, as appears from Fig. 5, that the thread or filling fails to be drawn down into the threading block on the first pick of the shuttle after the replenishing operation; and thereupon a real mistread occurs, that is to say, the filling breaks on the pick of the shuttle to the replenishing side of the loom. One of the features of the present invention is to render the threading of the shuttle on the first pick after replenishment more certain. This is effected by the novel form of the front wall of the shuttle box. The outer end or point 35 of the upper part 36 of the wall is upturned a substantial distance above the top of the shuttle, as shown in Fig. 5. The result is that as the lay beats backward after replenishment, the incoming filling end 46 is caught by the under side of the point 35 and is drawn down under the upper part 36 of the front box wall into the slot 39 as the shuttle is picked to the other side of the lay. This slot 39 is substantially on the plane of the shuttle eye 43. Consequently, while the shuttle is performing the first part of its flight after replenishment, the outer end of the filling is held at a point below the upper surface of the shuttle and the chances of the filling being drawn down into the threading block are greatly increased; and conversely, the chances of real mistreads occurring are correspondingly decreased. By the time the lay has reached its rear center the incoming filling end has been drawn entirely out of the replenishment shuttle box through the slot 39, owing to the relative movement between it and the lay.

When the shuttle has completed its first flight after replenishment and the warp threads have crossed for the next shedding, it is desirable to sever the incoming filling end adjacent the selvage as soon as possible thereafter, in order to prevent the filling end from being broken and whipped into the shed, and thereby cause a double pick. The usual device for severing the filling end adjacent the selvage is a temple thread cutter, indicated at 50, Fig. 2. The action of these temple thread cutters is necessarily somewhat uncertain, and, consequently in order to prevent the incoming filling end from being drawn or whipped into the shed before it is cut at the selvage, it is necessary to prevent the filling end from being chafed and broken by the replenishing shuttle box. This is accomplished by guiding the filling into the slot 39 in the front wall of the shuttle box so that the filling may readily enter the shuttle box and not chafe on the front wall thereof.

The filling is guided into the box by the inclined surface 51 of the inner end of the upper part 36 of the front box wall.

The devices of the present invention, which operate to prevent the filling end extending from the selvage to the bobbin in the shuttle when the latter has been boxed for the replenishing operation following an indication of predetermined exhaustion of the filling by the filling feeler mechanism, comprise means for grasping the filling at a point adjacent the shuttle eye and pulling it completely out of the replenishing shuttle box after it has been severed on the other side of the eye. This filling end is known as the outgoing filling end. The thread grasping or clamping means is adapted to hold the outgoing filling end until it has been severed at the selvage by the temple thread cutter. It is thus prevented from being drawn into the shed by the shuttle.

The mechanism for clamping and parting the outgoing filling end is composed of two separate parts, one of which performs only the clamping operation and the other of which performs only the severing operation. The thread clamping device comprises a lower fixed clamping jaw 53 and an upper movable clamping jaw 54. These clamping jaws are normally held in closed position relatively near the breast beam 55, as shown in Fig. 1, so as to be out of range of the lay, but are adapted to be opened and to be moved rearwardly toward the lay when the filling feeler mechanism indicates critical exhaustion of filling, so as to be in position to grasp the outgoing filling end in close proximity to the shuttle eye as the lay moves forward on the replenishing beat-up. In order that the clamping jaws may more effectually perform their thread grasping and clamping operation, the shuttle is cut away at 56 on the horizontal plane of the shuttle eye, and the relative movement of the clamping jaws and the lay is such that the rear or outer ends of the jaws enter the recess 56 before they close upon the filling thread. It will be observed that the likelihood of the clamping jaws grasping the filling at this point is much greater than it would be if they were positioned to operate at a point nearer the inner end of the shuttle box. In fact, experience has shown that the position of the filling thread at this point is so nearly positive and uniform that it is only necessary to provide a relatively small opening between the clamping jaws in order that they may grasp the filling. It will be readily understood, however, that the recess 56 may be widened and that the clamping jaws may be so constructed as to open wider if it is desired.

The lower clamping jaw is secured to the lower end of an arm 58 pivoted for swinging movements toward and from the

lay on a pin 59 fixed in the upper end of an upwardly extending part 60 of a bracket 61 secured on the outer end of the stud 13. The clamping jaws are moved from their normal position, as shown in Fig. 1, rearwardly toward the lay to their position for grasping the filling, as shown in Fig. 4, by means of an arm 63 which engages the forward side of a pin 64 projecting laterally from the inner side of the lower end of the arm 58. The arm 63 depends from and is secured to a rod 65, the outer end of which is journaled in the lower portion of the bracket 61, and the inner end of which is journaled in the hopper plate 9, as shown in Fig. 2. The rod 65 is oscillated so as to move the clamping jaws rearwardly toward the lay, by means of a hook 67 the barbed portion 68 of which engages the rear side of the upturned end 69 of the rod 65. The hook 67 is pivoted at its forward end on the pin 70 passed through the rear end of the angle piece 19. The under side of the hook 67 lightly rests on the upper end of the arm 17. When on the indication of predetermined exhaustion of filling, the hopper arm 11 swings outwardly, the hook 67 is thereby drawn to the left and the rod 65 and the arm 63 are oscillated in a direction to move the clamping jaws rearwardly. The rearward movement of the lower end of the arm 58 which carries the clamping jaws is not so great as the movement of the hook 67, so that when the clamping jaws have been moved to their rearward position for grasping the filling, the continued movement of the hook 67 has no effect upon the arm 63, because at this time the barb 68 of the hook is disconnected from the end 69 of the rod 65. This is effected by means of a cam piece 72 in fixed relation with the hook 67. The lower side of the cam piece 72 rests on the hub 73 of the arm 17, and the rear end thereof projects downwardly somewhat below the top surface of the hub 73, so that as the cam piece 72 and the hook 67 are moved forward with the hopper arm 11, the engagement of the cam piece 72 with the hub 73 causes the barb 68 of the hook to be disengaged from the end 69 of the rod 65, as shown in Fig. 2. In this figure the hopper arm is shown at the limit of its outward movement and the lay is on its front center. On the return of the hopper arm 12 to its normal position following the replenishing operation, the rear end of the hook 67 readily passes over the end 69 of the rod 65, and the parts are thereby returned to their normal position. Rearward movement of the upturned end 69 of the rod 65 is prevented by a stop pin 74.

The upper or movable clamping jaw 54 is pivoted on a pin 75 projecting outwardly from the arm 58. The upper clamping

jaw is opened and shut at the proper times with respect to the lower clamping jaw by means of a cam piece 77 pivoted at 78 on the arm 58. The upper end of the cam piece 77 is provided with a slot 79 which is adapted to be engaged by a pin 80 projecting outwardly from the bracket 61. On the front edge of the cam piece 77 is formed a projection 82 which is adapted, when the clamping jaws are moved rearwardly and the upper jaw is to be opened, to be moved into engagement with and to press against the upper end of the upwardly and forwardly projecting part 83 of the movable clamping jaw. On the rear edge of the cam piece 77 is formed the projection 84, which is adapted when the upper clamping jaw is to clamp the filling against the lower jaw, to be moved into engagement with a leaf spring 85 secured to the rear side of and projecting upwardly from the upper clamping jaw.

The mode of operation of the clamping jaws will now be understood from a consideration of Figs. 1 and 4. As the lower end of the arm 58 bearing the clamping jaws swings rearwardly toward the lay, by reason of the outward movement of the hopper arm 11 on the indication of predetermined exhaustion of filling, the front side of the slot 79 is forced against the front side of the pin 80, and thereupon the cam piece 77 is oscillated contra-clockwise and the projection 82 is forced against the part 83 of the upper jaw 54, so that the latter is oscillated in a direction to be opened. During this movement of the cam piece 77, the rearward projection 84 thereon passes out of engagement with the leaf spring 85, as shown in Fig. 4. The clamping jaws are now in position to receive the outgoing filling end 86 between them. During these movements the lay has been moving forward on the replenishing beat-up, and by the time the lay has nearly completed its forward movement, the outgoing filling end has been carried between the clamping jaws, as shown in Fig. 4, and the forward edge of a boss 87 on the lay has struck a shoulder 88 formed on the rearward side of the lower end of the arm 58. The continued forward movement of the lay causes the arm 58 to be swung toward the breast beam, and the rear side of the slot 79 to press against the rear side of the pin 80, so as to oscillate the cam piece 77 in a clockwise direction and force the projection 84 into engagement with the leaf spring 85. This closes the clamping jaws. By employing the leaf spring 85, the upper jaw is prevented from rebounding when it is first closed on the lower jaw. The filling is thereby prevented from escaping. It will be observed at this point that the lay does not move forward enough to push the arm 58 and the parts carried by it into normal po-

sition; other means is employed for this purpose. This means consists of a cam lever 90 pivoted at 91 on the bracket 61. A spring 92, one end of which engages the bracket 61 and the other end of which engages the upper side of the cam lever 90, tends to press the rear end of the cam lever downwardly. Two cam surfaces 93 and 94 are formed on the lower rearward end of the lever and are adapted to cooperate with a cam lug 95 projecting laterally from the arm 58. The engagement of the boss 87 on the lay with the shoulder 88 of the arm 58 pushes the latter forward far enough to force the cam lug 95 under the point 96 of the cam lever 90, and thereupon the force of the spring 91 is sufficient to cam the arm 58 into its normal position by means of the engagement of the cam surface 93 with the cam lug 95. Incidentally, the cam lever 90 holds the arm 58 and the parts carried by it in normal position. As the arm 58 is swinging forwardly into normal position, the projection 84 is forced downwardly against the forward side of the leaf spring 85 so that the upper jaw may exert a greater pressure against the lower jaw. By this means the outgoing filling end is firmly held. In the same manner that the cam surface 93 in cooperation with the cam lug 95 acts to complete the return of the arm 58 to its normal position, the cooperation of the cam surface 94 with the cam lug 95 acts to complete the movement of the arm 58 to its rearward position. The limit of the forward and the rearward movements of the arm 58 is determined by the engagement of the ends of the slot 97 formed in the arm 58 with the pin 80.

The movement of the clamping jaws toward the breast beam with the filling between them, by reason of the camming action of the lever 90, pulls the outgoing filling end through the slot 39 in the front wall of the shuttle box and substantially out of the shuttle box, as shown in Fig. 2. The part of the filling extending from the clamping jaws through the shuttle eye to the ejected bobbin 99 will also be drawn through the shuttle eye and completely out of the shuttle box, because as the lay beats backward, this part of the filling is severed immediately below the lay. The thread parting means comprises two cooperating parter blades, a fixed upper parter blade 100 and a movable lower parter blade 101. The upper parter blade 100 is mounted at its forward end on a pin 102 projecting laterally from the inner side of the lower end of an arm 103 extending downwardly from the bracket 61. This manner of mounting the upper parter blade is provided so that it may be readily removed if replenishment is to be controlled by the detector mechanism, in which case there is of course no outgoing filling end to sever. In order that the rear or cutting end of the upper blade may be held in operative position and yet have a slight movement up and down to accommodate the slight up and down movement of the lower movable parter blade, a lateral projection 104 on the forward end of the upper parter blade is received in a notch 105 in the lower end of the arm 103. The cutting edge 106 of the upper parter blade is offset laterally and inwardly from the rear end of the blade and is adapted to cooperate with the cutting edge 107 of the lower, movable parter blade. This lower parter blade is fulcrumed on a pin 108 fastened in a bracket 110 projecting downwardly and forwardly from the front of the lay. A spring 112 tends to press the rear or cutting edge 107 of the lower blade toward the lay. A lug 109 on the movable blade prevents it from striking the under surface of the lay, as shown in Fig. 5. This is so that the blade may not act as a clamp on the filling after it is severed. The upper fixed parter blade extends rearwardly toward the lay into the path of motion of the movable parter blade, and when the lay is on its forward center, the cutting edge 106 of the fixed parter blade is positioned considerably to the rear of the cutting edge 107 of the movable parter blade, as shown in Fig. 2. This is for the purpose of preventing the ejected bobbin from striking the cutting edge of the fixed parter blade. It will be observed by an inspection of Fig. 2 that the lateral position of the fixed parter blade is such that the inner edge 113 thereof is in the path of the filling end extending from the shuttle eye to the ejected bobbin 99. This filling end, therefore, must necessarily be closed upon by the parter blades as the lay beats back after the replenishing operation. The yielding mounting of the movable parter blade permits the fixed parter blade to pass between it and the under surface of the lay, and the spring 112 presses the cutting edge 107 of the movable blade firmly against the under surface of the fixed parter blade, so that, as the thread is caught between the two cutting edges it is severed. This severing of the thread takes place before the shuttle evacuates the shuttle box on the first pick after replenishment; consequently, when the shuttle is subsequently picked, the loose end of the filling is pulled through the shuttle eye because the end extending from the clamping jaws through the shuttle eye is relatively short.

After the lay has beaten backward following the replenishing operation, and thereby caused the severance of that part of the outgoing filling end extending from the clamping jaws through the shuttle eye to the ejected bobbin, the length of filling extending from the clamping jaws to the parting means is pulled through the shuttle eye and

hangs down from the clamping jaws, as indicated at 115 in Fig. 1. The part of the outgoing filling end 86 extending from the clamping jaws to the selvage is supported 5 until it is cut at the selvage by the temple thread cutter 50 by a support 116 which extends forwardly from the lay. This thread support 116 is for the purpose of preventing the outgoing filling end from being 10 chafed and broken by the bunter 15 and by projecting points on the lay. A guard 117 located on the opposite side of the bunter 15 from the support 116 is provided for the same purpose. The support 116 also serves 15 to guide the filling ends into the slot 39.

A brief recapitulation of the mode of operation of the various devices of the present invention in preventing the outgoing and incoming filling ends from being drawn or 20 whipped into the shed will serve to make clearer their cooperation. The mode of operation of the thread clamping and parting mechanism will be first described. It is assumed that the filling feeler mechanism has 25 indicated predetermined or critical exhaustion of the filling and that, therefore, the hopper arm 11 has been oscillated outwardly to position the transerrer latch 14 in the path of the bunter 15. The striking of the transerrer latch by the bunter causes the insertion of the filled bobbin 45 into the shuttle 40, and the ejection of the critically depleted bobbin 99 therefrom. The oscillation of the hopper arm 11 causes 30 the hook 67 to swing the clamping jaws rearwardly toward the lay, at the same time opening them to receive the outgoing filling end, when the shuttle has reached the requisite point on its forward movement. 35 When the lay beats up for the replenishing operation, the boss 87 thereon strikes the shoulder 88 on the lower end of the arm 58, carrying the clamping jaws, and starts the arm 58 forwardly toward its normal position. This forward movement of the arm 40 causes the upper clamping jaw 54 to close upon the filling, and thereafter the action 45 of the cam lever 90 under the influence of its spring 92, completes the return movement of the arm 58 and the clamping jaws to their normal position, and, at the same time, forces the upper jaw more tightly against the lower jaw so that the outgoing filling end will be firmly held. After the 50 replenishing operation takes place, the lay beats back, and during this backward movement of the lay, that part of the filling end extending from the clamping jaws through the shuttle eye down to the ejected bobbin 55 is severed immediately below the lay by the cooperative action of the thread parting blades 100 and 101. The part of the outgoing filling end extending from the selvage to the clamping jaws is thereafter held until it is severed at the selvage by the temple 60

thread cutter 50. The filling end is then held by the clamping jaws until the next replenishing operation. While the lay is retreating after the replenishing operation, the incoming filling end 46 extending from the hopper to the newly inserted bobbin is caught under the upturned point 35 of the upper part of the front box wall and is drawn down into the slot 39, so that the incoming filling end will be held in position 75 to be drawn down into the threading block in the shuttle.

The nature and scope of the present invention having been indicated, what is claimed as new is:—

1. A loom having, in combination, a lay, a self threading shuttle having an eye in its front side, weft replenishing mechanism, and a shuttle box at the replenishing end of the lay, said shuttle box having provision whereby as the shuttle is picked following the replenishing operation, the incoming filling end is guided down into the plane of the shuttle eye. 80

2. A loom having, in combination, a lay, weft replenishing mechanism, and a shuttle box at the replenishing end of the lay, said shuttle box having its front wall composed of two parts, the lower part being secured to the shuttle race of the lay and the upper part being supported at the inner end of the shuttle box only whereby the chances of the filling being drawn down into the filling block are increased, and the chances of a real mistread are decreased. 90

3. A loom having, in combination, a lay, a shuttle, weft replenishing mechanism, and a shuttle box at the replenishing end of the lay, said shuttle box having its front wall composed of two parts, the upper part being separated from the lower part by a narrow slot and supported at its inner end only, and having its outer end so arranged that as the lay beats backward following replenishment, the incoming filling end is 105 caught and drawn down into the slot. 110

4. A loom having, in combination, a lay, a shuttle, weft replenishing mechanism, and a shuttle box at the replenishing end of the lay, said shuttle box having in its front wall 115 a longitudinal slot lower than the top of the shuttle, and said shuttle box having provision for engaging the incoming filling end on the backward beat of the lay following replenishment and drawing the filling down into the slot. 120

5. A loom having, in combination, a lay, weft replenishing mechanism, loom controlling devices, a shuttle box at the replenishing end of the lay having an open ended slot in its front wall, and means operating on the replenishing beat-up of the lay to clamp the outgoing filling end at a point outside the shuttle immediately adjacent the shuttle eye and draw the filling end intact 130

from the selvage to the clamping means toward the breast beam.

6. A loom having, in combination, a lay, weft replenishing mechanism, loom controlling devices, a shuttle box at the replenishing end of the lay constructed to permit the filling to be drawn therefrom, thread clamping means arranged to clamp the outgoing filling end at a point outside the shuttle 10 immediately adjacent the shuttle eye and draw it, intact from the selvage to the clamping means, toward the breast beam on the replenishing beat-up of the lay, and means for severing the outgoing filling end between the shuttle and the ejected bobbin.

7. A loom having, in combination, a lay, weft replenishing mechanism, loom controlling devices, a shuttle box at the replenishing end of the lay having its front wall so constructed that when the shuttle is boxed the eye of the shuttle is beyond the outer end of the front wall, means for clamping the outgoing filling end between the outer end of the front wall of the shuttle box and the shuttle eye, and means for severing the filling between the clamping means and the ejected bobbin.

8. A loom having, in combination, a lay, a shuttle, weft replenishing mechanism, loom controlling devices, a shuttle box at the replenishing end of the lay, a single means arranged to clamp the outgoing filling end only at a point outside the shuttle immediately adjacent the shuttle eye and draw it 30 toward the breast beam, the filling being intact from the selvage to the clamping means, said shuttle box having provision whereby the outgoing filling end is permitted to be drawn therefrom intact, and means 40 for severing the filling between the shuttle and the ejected bobbin.

9. A loom having, in combination, a lay, a shuttle, weft replenishing mechanism, loom controlling devices, a shuttle box at the replenishing end of the lay having its front wall so constructed that when the shuttle is boxed the shuttle eye is beyond the outer end of the shuttle box, a single clamping means arranged to clamp the filling only at a point 45 between the outer end of the front wall of the shuttle box and the shuttle eye, means for severing the filling between the clamping means and the ejected bobbin, and means for severing the filling at the selvage.

10. A loom having, in combination, a lay, a shuttle, weft replenishing mechanism, loom controlling devices, a shuttle box at the replenishing end of the lay having an open ended slot extending throughout the 60 length of its front wall, clamping means for engaging the outgoing filling end and drawing it through the slot, and means for severing the filling at a point between the shuttle and the ejected bobbin.

11. A loom having, in combination, a lay,

a shuttle, weft replenishing mechanism, loom controlling devices, a shuttle box at the replenishing end of the lay having its front wall composed of two parts separated by a narrow, longitudinally extending slot, means 70 operating when the shuttle has been boxed for the replenishing operation to clamp the outgoing filling end at a point immediately adjacent the shuttle eye, and means for severing the filling between the clamping 75 means and the ejected bobbin, the upper part of the front wall of the shuttle box having provision to engage the incoming filling end on the backward beat of the lay after replenishment and direct it through the slot. 80

12. A loom having, in combination, a lay, weft replenishing mechanism, loom controlling devices, and a thread clamping mechanism comprising a bracket, an arm pivoted thereon, a clamping jaw fixed on the arm, a 85 movable clamping jaw pivoted on the arm, a cam piece having a slot, a pin in the bracket engaged by the slot, and means connected with the loom controlling devices for swinging the arm toward the lay, the arm being 90 swung toward the breast beam by the lay, said movable jaw being opened by the cam piece as the arm swings toward the lay, and shut by the cam piece as the arm swings toward the breast beam.

13. A loom having, in combination, a lay, weft replenishing mechanism, loom controlling devices, and a thread clamping mechanism comprising a bracket, an arm pivoted on the bracket, a clamping jaw fixed on the 100 arm, a movable clamping jaw pivoted on the arm, means for opening and shutting the movable clamping jaw, means connected with the loom controlling devices for swinging the arm toward the lay, the arm being 105 swung toward the breast beam by the lay, and a cam lever for completing the movement of the arm toward the lay and its movement toward the breast beam.

14. A loom having, in combination, a lay, a self-threading shuttle having a threading block in its top side and an eye in its front side, weft replenishing mechanism, and means on the lay for guiding the incoming filling end down into the plane of the shuttle 115 eye as the shuttle is picked following the replenishing operation.

15. A loom having, in combination, a lay, weft replenishing mechanism, and a shuttle box at the replenishing end of the lay having a two-part front wall to provide a slot for the incoming weft the upper part of which is 120 adjustably supported at its inner end on the inner end of the shuttle box.

16. A loom having, in combination, a lay, weft replenishing mechanism, a shuttle box at the replenishing end of the lay having a front wall provided with a longitudinal slot, extending throughout the length of the wall, and a support secured to the lay to guide 125 130

filling ends extending outwardly from the selvage and supported at their outer ends beyond the front box wall, into the slot on the forward beat of the lay.

- 5 17. A loom having, in combination, a lay, weft replenishing mechanism, and a shuttle box at the replenishing end of the lay having a two-part front wall the upper part of which is supported only at the rear of the 10 box, said front wall of the shuttle box having provision for permitting the escape of

the intact incoming filling end from the box.

18. A loom having, in combination, a lay, a shuttle box, a self-threading shuttle having 15 an eye in its front side, weft replenishing mechanism, and means on the lay for guiding the incoming filling end into the shuttle box substantially on the plane of the shuttle eye during the pick following replenishment. 20
